UNITED STATES PATENT OFFICE

ALEXANDER DICKSON, OF BROOKLYN, NEW YORK

SKELETON FRAME FOR WALL CONSTRUCTIONS

Application filed August 7, 1928. Serial No. 297,994.

The invention relates to walls of the type shown in my U. S. Patent No. 1,301,110 of April 22, 1919, and it aims to provide a new and improved construction in which the laths present plastic-receiving troughs and inwardly declined surfaces above said troughs for guiding the plastic into them as it is applied.

A further object is to provide unique means for anchoring the ends of the lath-supporting studs.

With the foregoing in view, the invention resides in the novel subject matter herein-after described and claimed, description being supplemented by the accompanying drawings.

Fig. 1 is a side elevation of a wall partly broken away to more clearly disclose the skeleton framework.

Fig. 2 is a vertical sectional view on line 2—2 of Fig. 1.

Fig. 3 is a horizontal section on line 3—3 of Fig. 1.

Fig. 4 is a sectional perspective view of two of the laths and a portion of one of the studs.

Fig. 5 is a disassembled perspective view of a portion of one of the studs and one of the stud-anchoring brackets.

Fig. 6 is a sectional perspective view showing the manner in which the stud and the bracket are secured together.

Fig. 7 is a horizontal sectional view on line 7—7 of Fig. 6.

Fig. 8 is a view similar to Fig. 4 but showing a slightly different form of construction.

Fig. 9 is a sectional perspective view illustrating a form of stud which is preferably employed when the wall constitutes a veneer on a pre-constructed wall.

Figs. 10 and 11 are sectional perspective views illustrating further modifications.

The construction illustrated in Figs. 1 to 7 will first be described. In these views, 12 denotes the vertical studs which are of light

channel metal. Each stud is formed with vertically spaced lath-receiving openings 13 whose lower edge walls incline longitudinally in opposite directions as indicated at 14 and 14a respectively. Receivable in the openings 13, are laths 15 each formed of a light metal strip bent into the form of a trough. Not only does this construction provide upwardly opening channels or troughs to receive the plastic material but it provides the laths 15 with inwardly declined external surfaces 16. When the plastic material is applied to the skeleton framework formed by the laths and studs, these inwardly declined surfaces 16 direct the plastic downwardly into the subjacent troughs or channels.

The lower edge walls of the openings 13 inclined from their centers to their ends as indicated at 14 and 14a, and these inclinations are more steeply inclined than the outer sides 16 of the laths 15, so that portions of said edge walls are receivable in notches 17 formed in the longitudinal edges of the laths. These notches hold the laths against endwise sliding after they are once in place and hence the laths serve to tie the studs 12 together.

For anchoring the ends of the studs 12, I provide L-shaped brackets 18 preferably formed of light channel metal. The horizontal portion of each bracket is adapted for anchorage to a floor or ceiling joist or to other support. The vertical portion of the bracket is adapted to contact with an end of the stud 12 and is formed with a lath-receiving openings 19 for alinement with a number of the openings 13. Tongues 20 are formed integrally with the vertical portion of the bracket at opposite sides of its openings 19. These tongues are bent laterally through the openings 13 and clinched as shown in Fig. 7 for the purpose of securing the stud to the bracket. This bracket and its associated details of construction provide simple and in-

expensive means for easily and rapidly anchoring the ends of the studs 12.

After securing the studs in place, the metal laths 15 are slipped into the openings 13 and some of the notches 17 are engaged with the edge walls 14-14a of the studs, thereby effectively tying the latter together and holding the laths against accidental longitudinal movement. Plastic material is now applied to one side of the skeleton framework and during such application, the plastic is downwardly directed into the troughs of the laths by the overlying inwardly declined surfaces 16. The plastic is applied in such abundance that it runs through on the opposite side of the skeleton framework. This surplus is then roughly spread at that side of the wall and in this manner, the spaces between the laths are in a roughly filled condition, with the mortar effectively supported by the trough-shaped laths. When this mortar has set sufficiently, a rough coat is applied to both sides of the wall and for most uses a finishing coat is then added. The completed wall is fire-proof, crack-proof, vermin-proof and exceptionally rigid. It is intended primarily for partitioning, but is not restricted to this particular field of use.

Fig. 8 discloses a construction in which the openings 13b of the stud 12b have their lower edges shaped to snugly contact with the trough-shaped laths 15b. These laths are formed with spaced openings 17b and lugs 21 are formed integrally with the lower edge walls of the openings 13b for reception in said openings 17b. These lugs 21 and openings 17b perform the same functions as the openings or notches 17 and the co-acting portions of the stud 12.

Fig. 9 discloses a construction in which the openings 13c of the stud 12c are in the form of notches, the stud being of light angle metal instead of channel metal. This stud is usable primarily when veneering old walls, a number of the studs being secured to the wall and the laths being then conveniently laid in the openings 13c.

In Fig. 10, the stud 12d is formed with a plurality of circular openings 13d disposed in vertically spaced pairs, and semi-cylindrical trough-shaped laths 15d are receivable in said openings. This form of construction is very analogous to that shown for instance in Figs. 4 and 8, as the lower edge walls of the openings 13d are longitudinally inclined from their centers to their ends, as indicated at 14d and 14e respectively, and the laths 15d not only present upwardly opening channels but also present inwardly declined external surfaces 16d.

In Fig. 11, the laths are in the form of solid metal rods 15e supported by reception in the openings of a stud 12e which is identical with the stud 12d. The laths 15e are in such close relation horizontally that vir-

tually a trough 15f is formed between the laths or rods of each pair, and the curved peripheral portions 16e of these rods or laths, serve to downwardly guide the plastic into these troughs as it is applied. Hence, though quite different in appearance, there is marked analogy between this form of the invention and the other forms previously described.

Excellent results are obtainable from the general construction shown and described and the present disclosure is therefore preferably followed. However, within the scope of the invention as claimed, variations may be made.

I claim:

1. A skeleton frame for wall construction, comprising vertical studs having vertically spaced lath-receiving openings, and laths passing through said openings, said laths providing upwardly opening plastic-receiving troughs throughout their lengths and inwardly declined external surfaces over the troughs, each of said inwardly declined surfaces serving to downwardly direct plastic material into the subjacent trough when said material is applied.

2. A skeleton frame for wall construction, comprising vertical studs having vertically spaced lath-receiving openings, the lower edge wall of each opening being inclined in opposite directions, and vertically spaced laths passing through said openings, each lath being of trough-shape and presenting external inwardly declined surfaces, said inwardly declined surface of each lath serving to downwardly direct plastic material into the trough of the subjacent lath when said plastic is applied.

3. A structure as specified in claim 2; said laths and studs having interlocking portions holding the laths against longitudinal sliding.

4. A structure as specified in claim 2; said laths having openings receiving portions of said studs to hold the laths against longitudinal sliding.

5. A structure as specified in claim 2; said lower edge wall of each opening being more steeply inclined than said external surfaces of the laths, edges of the latter being formed with notches receiving portions of said lower edge walls of the openings to hold the laths against longitudinal sliding.

6. A stud having vertically spaced lath-receiving openings, the lower edge wall of each opening constituting a lath support and being longitudinally inclined from its center to its ends.

7. In a wall framework, a stud having lath-receiving openings, an L-shaped anchoring bracket whose vertical portion lies against said stud, said vertical portion of the bracket being formed with a lath-receiving opening registering with one of the aforesaid openings of the stud, and a tongue in-

tegral with the bracket at the edge of its opening, said tongue being bent through said one opening of the stud and clinched to secure bracket and stud together.

5 8. An L-shaped stud-anchoring bracket having a lath-receiving opening in its vertical portion, and an integral tongue at an edge of said opening for securing a stud to the bracket.

10 In testimony whereof I have hereunto affixed my signature.

ALEXANDER DICKSON.
